CLAIM

The ornamental design for a microbiological test tray
carrier, as shown and described.

DESCRIPTION

FIG. 1 is a perspective view of a microbiological test
tray carrier showing our new design;

FIG. 2 is a perspective view of the carrier of FIG. 1
rotated 180°;

FIG. 3 is a top plan view thereof;

FIG. 4 is a rear elevational view thereof;

FIG. 5 is a right side elevational view thereof;

FIG. 6 is a bottom plan view thereof;

FIG. 7 is a front elevational view thereof; and

FIG. 8 is a left side elevational view thereof.
